Inventor

Mason Fenwick Lawrence,

Attorney.

UNITED STATES PATENT OFFICE.

EDWARD ECKL, OF LOS ANGELES, CALIFORNIA, ASSIGNOR TO LOS ANGELES BREWING COMPANY, OF LOS ANGELES, CALIFORNIA, A CORPORATION OF CALIFORNIA.

DESIGN FOR A BOTTLE.

58,077.

Specification for Design. Patented June 7, 1921.

Application filed July 30, 1919. Serial No. 314,349. Term of patent 3½ years.

To all whom it may concern:

Be it known that I, EDWARD ECKL, citizen of United States of America, residing at Los Angeles, in the county of Los Angeles and State of California, have invented a new, original, and ornamental Design for Bottles, as shown in the accompanying drawing and described in the following specification.

The figure is a front elevation of a bottle showing my new design.

I claim:

The ornamental design for a bottle as shown.

EDWARD ECKL.

Witnesses:

LEO F. REISER,
JOSEPH AULENBROCK.
